UNITED STATES PATENT OFFICE.

JOHANN SCHUETTE, OF ZEESEN-KOENIGS-WUSTERHAUSEN, NEAR BERLIN, GERMANY, ASSIGNOR, BY MESNE ASSIGNMENTS, TO AMERICAN INVESTIGATION CORPORATION, OF NEW YORK, N. Y., A CORPORATION OF MARYLAND.

AIRSHIP.

1,420,768.

Specification of Letters Patent. Patented June 27, 1922.

Application filed June 25, 1919. Serial No. 306,726.

To all whom it may concern:

Be it known that I, JOHANN SCHUETTE, citizen of the German Republic, residing at Zeesen-Koenigs-Wusterhausen, near Berlin, Germany, have invented certain new and useful Improvements in Airships, (for which I have filed an application for patent in Germany March 1, 1913,) of which the following is a specification.

10 My invention relates to improvements in airships.

In the construction of air ships it is old to make the keel, serving to increase the longitudinal stiffness of the craft, in form of a gangway. Such keel was heretofore arranged outside of the framework or the envelope body, which, however, resulted in numerous disadvantages. Such an outside keel, on the one hand, is readily subject 20 to being injured in landing, and on the other hand, it naturally will considerably increase the height of the craft, which should be avoided as far as possible with regard to leeway, a good horizontal steering capacity 25 and a greater facility of holding the craft to the ground against the wind.

Contrary to such old constructions, the present invention provides that the gangway keel is disposed not as usual outside of 30 the gas-envelope body, but within the same. By such arrangement the disadvantages mentioned above are avoided and it is furthermore obtained that such keel is less exposed to tensile and compression strains 35 than when arranged outside of the airship, as in the latter case the lower longitudinal beam is, by the height of the keel, further away from the neutral axis than all longitudinal beams in the lower portion of the 40 frame work of the respective airship.

In the accompanying drawing the invention Fig. 1 is a longitudinal view of an airship without envelope. Fig. 2 is a cross sec-

tion of the same on a larger scale. Fig. 3 a constructional form of the keel, likewise 45 on a larger scale, and Fig. 4 is a plan of Fig. 3. Figs. 5 and 6 two other modifications of the keel according to the present invention.

As shown in the drawings the gangway 50 keel *a* is disposed within the lower portion of the inwardly braced gas-enveloping frame *b*, from which the cars or gondolas are suspended. The keel *a* extends from stem to stern; it is composed in known 55 manner of longitudinal beams *c*, ties *d* and braces *e*, of which the latter two are only partly shown in Fig. 1. In the constructional form according to Figs. 2, 3 and 4 the keel has the shape of a triangle, it may 60 however also be made of a trapezoid section, Fig. 5 or of a curved section, Fig. 6. The design of the gangway itself is such, that the same will meet its purpose as keel of the airship. 65

What I claim is:

1. In a rigid airship, a rigid gas-enveloping frame, a supplemental heavy and rigid strengthening frame formed integral with the bottom portion of said rigid gas-enveloping frame and being enclosed thereby, said supplemental frame constituting a keel 70 and having a chamber or passage extending longitudinally of the airship.

2. In a rigid airship, a rigid gas-enveloping frame having a plurality of sectors, a supplemental heavy and rigid strengthening frame mounted in one of said sectors and formed integral with the said rigid gas-enveloping frame, said supplemental frame 75 constituting a keel and having a chamber or passage extending longitudinally of the airship. 80

In testimony whereof I have affixed my signature.

JOHANN SCHUETTE.
